UNITED STATES PATENT OFFICE.

PETER LANDFRIT, OF CINCINNATI, OHIO.

HARNESS-LOOP MACHINE.

SPECIFICATION forming part of Letters Patent No. 299,406, dated May 27, 1884.

Application filed May 29, 1882. (Model.)

To all whom it may concern:

Be it known that I, PETER LANDFRIT, of Cincinnati, Hamilton county, State of Ohio, have invented certain new and useful Improvements in Machines for Finishing Harness-Loops, of which the following is a specification.

My invention relates to the mechanism for finishing the various-sized loops on harness, and has reference in general, first, to the formation of the dies whereby the various loops are finished, and, secondly, to a peculiar form of clamp for holding said dies. By the means now employed it is a difficult matter to finish the harness-loops, and especially those on the bridle-blinds and on straps of greater width than the loop, in such a manner as to give them a symmetrical appearance; and the object of my invention is to overcome these difficulties.

Referring to the drawings forming part of this specification, Figure 1 is a top view of the clamp for holding the various dies. Fig. 2 is a side or edge view of the same, showing a harness-loop clamped therein. Fig. 3 represents one of the harness-loops as finished. Fig. 4 is an edge view of the clamp with the dies shown in position thereon. Fig. 5 represents in perspective the dies for forming short loops, the same dies being shown in Fig. 4 in position on the clamp. Fig. 6 is a top view of the clamp having attached thereto the dies or jaws to be used for forming the loop on a bridle-blind. Fig. 7 is an edge view of Fig. 6. Figs. 8 and 9 represent the jaws shown in Figs. 6 and 7 detached from the clamp.

A is the body of the clamp, at one end of which is formed the stationary jaw A', and to the opposite end of the body is adjustably secured the sliding jaw A².

As the sides of the loops to be formed are, as at present, made parallel to each other and at right angles to the top and bottom of the loop, the faces of the jaws A' A² stand in a plane at right angles to the face of the body A. The jaw A² is provided with the arms or extensions a, in each of which is formed a longitudinal slot, a', through which slots pass bolts b, which latter are secured to the body A, and upon which are thumb-nuts b', washers

b² being interposed between the thumb-nuts and the face of the arms a, the washers being wide enough to rest on the arms at each side of the slot a', so that when the thumb-nuts are screwed down tightly upon the washers the arms a will be tightly clamped, and by this construction the jaw A² may be moved toward or away from the stationary jaw A' and secured firmly in the desired position. This adjustable jaw is moved back and forth by any suitable means, preferably by a screw, B, which passes through a raised nut, B', connected to or forming a part of the body A, one end of said screw being secured to the jaw A² in such a manner as to be permitted to turn therein and yet be secured thereto, so that as the screw B is turned in the nut B' the jaw A² may be moved in the desired direction. The free end of this screw B is provided with a crank or hand wheel, C, by means of which it is turned. The side of the sliding jaw A² is provided with lugs or feet D, which rest and slide upon the upper surface of the body A, and keep the jaw raised a space, w, above the body; and at the lower edge of the stationary jaw A' is the channel d, extending the entire length of the jaw, and equal in width to the distance at which the sliding jaw is held above the body A. If, now, it is desired to use the clamp for finishing loops on a straight strap, as represented by Fig. 3, the jaws above described are sufficient for the purpose. A stick or core, E, of the desired width and thickness, is slipped into the loop, and the latter is then placed upon the body A against the stationary jaw A', the channel d permitting the side of the loop to rest closely against the said jaw. Should the strap to which the loop is attached be, as is frequently the case, somewhat wider than the loop itself, that part of the edges of said strap which project beyond the sides of the loop will be respectively received into the channel d and space w. The sliding jaw A² is now moved up by means of the screw B until it rests closely and firmly against the opposite side of the loop. A die, E', having a plain face, or one designed to form an appropriate figure on the face of the loop, is now placed between the jaws A' and A², the face of the die resting upon the loop, and this die is then pressed by any appropriate mechanism firmly

down upon the loop, which, being firmly held between the jaws A' and A'' , is thus caused to assume a symmetrical shape.

A very convenient form of press to be used in connection with my invention is the ordinary bench-vise found in all shops, as my invention may readily be placed in such a vise, and in small shops which have no other presses this will be found to be of great advantage.

10 In finishing short loops I preferably employ the supplemental jaws, F F' , shown in Fig. 5. The jaw F is connected to a base-plate, e , and a channel, d , similar in formation and purpose to the channel d at the lower edge 15 of the stationary jaw A' , is formed in the angle between the jaw F and the base-plate e . This base-plate e is placed on the upper face of the body A , the back of the jaw F resting against the face of the stationary jaw A' , occupying the position shown in Fig. 4, in which position the jaw F serves the purpose of the stationary jaw. The jaw F' is provided with a flange, f , which hooks over the upper edge of the sliding jaw A'' . The flange f preferably has a notch, f' , which, when the jaw F' is to be used, engages with a lug, e' , on the upper edge of the sliding jaw A'' , thus preventing the jaw F' from slipping longitudinally on the jaw A'' . When these supplemental jaws 25 are employed, the finishing of the loop is effected in a manner similar to that before described.

While I have thus fully described the jaws F F' , I do not make any claim for them in this 30 application, as I purpose making them the subject of separate Letters Patent.

It has heretofore been a difficult matter to procure a perfect and symmetrical finish on the long loop which is attached to one edge of 35 the bridle-blinds, owing to the difficulty in bringing any pressure to bear against the sides of the loop, in consequence of its position with relation to the blind; but I accomplish this in a perfect manner by the use, in connection with 40 the clamp, of the supplemental jaws shown in Figs. 6 to 9, which jaws, when they are to be used, are suitably connected to the jaws A' A'' , a very convenient mode of so connecting these supplementary jaws being that shown in 45 the drawings.

The jaw G , consisting of a base, g , and a face, g' , is attached to the stationary jaw A' . This jaw G is provided with feet G' , which rest on the body A of the clamp and elevate the base g , upon which the loop is to rest, and on the back of the face g' are the dovetailed flanges or lugs h , which latter are usually placed (when the jaw G is to be employed) at each end, respectively, of the stationary jaw 50 A' , the ends y of which, or equivalent projection on said jaw, are dovetailed, as shown in Fig. 6, so as to fit snugly between the lugs h . Another jaw, J , is connected to the sliding jaw A'' . This jaw J consists of a body, j , and 55 a head or face, k , the head being connected to the body by the arches k' , so formed as

to raise the face k up to a level with the face g' of the jaw G . This jaw J is retained in position on the sliding jaw A'' by means of dovetailed flanges m on the back of the body 70 j , which flanges engage with the projections formed on, and preferably identical with, the ends of the sliding jaw, which are dovetailed to correspond with the formation of said flanges. Between the body j and the head k of the die 75 J is an opening, H , through which the blind is to be placed; and when it is placed in this position and the sliding jaw moved up until the loop is clamped between the jaws G and J , the parts occupy the position shown in Fig. 80. By the use of these supplemental jaws, G and J , in connection with the clamp, I am enabled to finish the loop on the blind in a manner similar to that described for finishing a loop on a straight strap, and with an equal 85 degree of perfection.

By the employment of the clamp and the jaws above described it will be seen that any of the loops upon a harness may be perfectly shaped.

If it is desired to stamp any particular design on the sides of the loops, the faces of the jaws may be formed accordingly.

Having thus described my invention, what I claim as new and of my invention, and desire to secure by Letters Patent, is as follows:

1. The base or frame A , having jaw A' , provided with projections y , and sliding jaw A'' , having projections X , adapted to receive interchangeable jaws or dies, in combination 100 with arms a , having slots a' , and nuts b , and screw B , substantially as and for the purposes specified.

2. The body A , provided with stationary jaw A' , and the bolts b , having thumb-nuts b' , 105 in combination with the sliding jaw A'' , provided with arms a , having slots a' , to engage with said bolts, and means for advancing and retracting said sliding jaw, substantially as and for the purposes specified.

3. The body A , having stationary jaw A' and channel d , and the stationary nut B' , in combination with the sliding jaw A'' , provided with the feet or lugs D , resting on the body A at or near the edge thereof, and means for 115 advancing and retracting said sliding jaw, substantially as and for the purposes specified.

4. The herein-described clamp, in combination with the supplemental stationary jaw G , attached to the jaw A' , and the supplemental sliding jaw J , connected to the jaw A'' , the jaw J consisting of the body j and the head or face k , an opening, H , being left between said body and head, substantially as and for the purposes specified.

5. The jaw J , provided with longitudinal slot, in combination with the jaw A'' of the clamp, and the slotted arms a , and the clamping-bolts b , and thumb-nuts b' , and screw B , substantially as and for the purposes specified.

6. In combination with the jaw A'' of the clamp, having dovetail projections X , the jaw

J, provided with longitudinal slot, and with dovetail flanges *m*, fitting over the projections X, substantially as and for the purposes specified.

5 7. The jaw G, provided with feet G', and attached to the jaw A', in combination with the jaw J, attached to the jaw A², and con-

sisting of a body and head, *h*, the head being raised above the body by the arches *k*, substantially as and for the purposes specified.
